UNITED STATES PATENT OFFICE.

ELMER AUGUSTUS PARRISH, OF BALTIMORE, MARYLAND, ASSIGNOR OF
ONE-HALF TO JAMES A. BROOKS, OF SAME PLACE.

CLOTHES-HORSE.

SPECIFICATION forming part of Letters Patent No. 403,066, dated May 7, 1889.

Application filed January 17, 1889. Serial No. 296,683. (No model.)

To all whom it may concern:

Be it known that I, ELMER AUGUSTUS PARRISH, a citizen of the United States, residing at Baltimore, in the State of Maryland, have 5 invented certain new and useful Improvements in Clothes-Horses, of which the following is a specification.

This invention relates to an improved clothes-rack, and will first be described, and 10 then designated in the claims.

In the accompanying drawings, Figure 1 is an elevation of the rack. Fig. 2 is a view of one arm and bracket-hook. Fig. 3 is a top view of the rack. Fig. 4 is another elevation 15 of the rack and shows an additional feature. Fig. 5 shows the foot for the bracket-hook.

The letter A designates a square post or standard, and b the stand or supporting-feet. Each arm C has a bracket-hook, d, attached, 20 the arm and bracket being connected at right angles to each other. At the point of the angle a hinge, e, is attached and makes connection with one side of the post. The four sides of the post have these combined arms 25 and bracket-hooks hinged thereto. When the arms C are extended horizontally, the bracket-hook d serves as a brace or support, and the arms are adapted for hanging thereon articles of clothing and household linen to be 30 dried. When the arms are not required for this purpose, they may be turned upward vertically and take position close against the side of the post, and thereby cause the bracket-hooks d to project laterally, enabling them 35 to serve as short hooks for small articles. Small hooks f hang at the corner edge of the post, and each takes into a staple, g, on the arm C and confines the latter to its vertical position.

An additional feature is shown in Fig. 4. 40 Here provision is made for independent adjustment of the arms C, so that any one of them alone may be extended horizontally or turned up without regard to the position of the other arms. This is effected by having 45 the bracket-hook d attached to the arm C at a point a short distance from the hinged end—far enough from said end to form an offset, h, at the back of the bracket-hook equal to the thickness of the arm—and then attaching 50 a straddle-foot, i, to the extremity of the bracket-hook. The foot i is made of metal and straddles the turned-up arm C, that is next below, as shown.

Having described my invention, I claim— 55

1. A rack having in combination the post A, the arms C, each having attached a bracket-hook, d, the arm and bracket being connected at right angles to each other, and a hinge, e, connecting the arm and hook to 60 the post, as shown and described.

2. A rack having in combination the post A, the arms C, each having attached a bracket-hook, d, the arm and bracket being connected at right angles to each other and having 65 an offset, h, at the back of the bracket-hook, a hinge, e, connecting the arm and hook to the post, and a foot, i, attached to the bracket-hook to straddle a turned-up arm next below. 70

In testimony whereof I affix my signature in the presence of two witnesses.

ELMER AUGUSTUS PARRISH.

Witnesses:

JOHN E. MORRIS,
JNO. T. MADDOX.
